CAR DOOR

Filed Nov. 14, 1925

Inventor
Thomas F. Tracy
By Ben Deeman v. Latte Mfg.

UNITED STATES PATENT OFFICE.

THOMAS F. LACY, OF SIOUX CITY, IOWA.

CAR DOOR.

Application filed November 14, 1925. Serial No. 69,009.

My invention relates to door construction in railway cars, particularly stock cars and box cars, and has for its object to provide a door for such a car which may be easily 5 opened and closed without binding or sticking.

Another object is to provide such a door construction which is of simple, durable and inexpensive construction.

- 10 More particularly, it is my object to provide such a construction in which the weight of the door is supported at its bottom by a rail upon which the door slides longitudinally and relative to which the door is capable of limited lateral or transverse movement allowing the door to be swung away from the door frame without interfering with the slidability of the door longitudinally of the rail.
- 15 A further object is to provide means to prevent removal of the door from the rail, to limit its transverse movement relative to the rail, and to lock it in its inner position contiguous to the door frame.

- 20 A still further object is to provide a combined guide and water shed for the upper extremity of the door, of such nature as to brace the door against impact from within.
- 25 With these and other objects in view, my invention consists in the construction, arrangement and combination of the various parts of my device whereby the objects contemplated are attained, as hereinafter more fully set forth, pointed out in my claims 30 and illustrated in the accompanying drawings, in which:

Fig. 1 is a side elevation of a portion of a car embodying my invention.

Fig. 2 is a vertical sectional view of the same, taken on the line 2—2 of Fig. 1.

Fig. 3 is a detail sectional view of the caster and rail connection, taken transversely of the rail.

Fig. 4 is a side elevation of the latter, parts 45 being broken away to better illustrate the construction.

Fig. 5 is a detail sectional view, taken on the line 5—5 of Fig. 1.

I have used the reference character 10 to 50 indicate generally the body of a car which has a door opening framed by casing uprights 11 and 12, and horizontal joists, 13 and 14. A rail, 15, of tubing or the like, is supported by three brackets, 16, 17 and 55 18, secured to the lower joist, 14.

The door, 19, is supported on the rail, 15,

through the medium of casters, A and B, which each include a bracket, 20, having a face plate, 21, secured to the lower corners of the door, as at 22. The respective brackets of the casters, A and B, extend away from the door in opposite directions, for a purpose which will be hereinafter more fully explained. Downwardly opening sockets, 22, are formed on the ends of the brackets. 60 65

The sockets, 22, are provided in their sides, with bearing slots, 23, (see Fig. 4) which receive the trunnions, 24, of rollers, 25, which are thus mounted transversely of the rail so as to roll thereon. 70

Referring now to Fig. 3, it will be noted that the rollers, 25, are of such length that they may be shifted transversely of the rail a limited distance between two limits, in either of which position the rollers will roll upon the rail. In order to limit such shifting, and to also prevent removal of the door from the rail, I provide for each caster, a sleeve, 26, cut away as at 27 so as not to interfere with the rollers, and provided with spaced ears, 28 and 29, between which are received the respective sockets, 22. 75 80

The ears, 28 and 29, are provided with slots, 30, through which studs, 31, are threaded into the sockets, 22. Lugs, 32 and 33, on the inner and outer sides, respectively, of the sockets, project from the ends of the sockets to receive between them the respective ears, 28 and 29. 85

The upper extremity of the door is provided with an upwardly projecting rib, 34, substantially flush with the inner face of the door. The rib, 34, has a shoulder, 35, covering the upper edge of the door, and terminating in a downwardly projecting flange, 36, by means of which the rib, 34, is secured to the door. 90 95

A guide, C, is formed by a Z-shaped plate, 37, secured, together with a flat plate, 38, to the joist, 13, in such relation that a downwardly opening channel is formed between the two plates. The rib, 34, is received in this channel, and it will be seen that any rain water flowing down the side of the car will be shed from the plate, 37, to the shoulder, 35, and thence down the outer face of the door, since the rib, 34, prevents such water obtaining access to the inner surface of the door. 100 105

At the same time, the rib, 34, is so connected to the door that impact against the door from within will have no effect in loos-

ening such connection. This is due to the fact that the rib is secured to the forward face of the door.

The guide, C, is substantially of equal length with the rail, and allows the door to be slid longitudinally on the rail, retaining the upper edge against outward displacement. It will be noted from Fig. 5 that a sufficient space is left for play vertically between the door and guide, C, to allow some tilting of the door vertically without binding. Such tilting might be caused by sagging of the track. The play also will allow the door to slide without binding should the upper guide become sagged.

Returning now to the caster construction, it will be seen by inspection of Fig. 3 that with the weight of the door resting on the rollers, 25, the inner limit of movement of the caster relative to the rail will be determined by engagement of the upper portions of the ears, 28 and 29, against the upper inclined face, 38^a, of the lug, 32, and by engagement of the lower portions of the ears, 28 and 29, against the lower inclined portion, 39, of the lug, 33.

When it is desired to pull the door away from the car frame, the handle, 40, is grasped and the door pulled outwardly, the rollers, 25, sliding transversely of the rail, 15, and the sleeves, 26, pivoting around the rail to a position where the upper portion of the ears, 28 and 29, engage the inclined faces, 39^a, of the lugs, 33, and the lower portions of said ears engage the lower inclined faces, 38^b, of the lugs, 32. This position is indicated in dotted lines in Fig. 2.

Sufficient space is left between the rib, 34, and the sides of the guide, B, to allow slight tilting of the rib relative to the guide, so that upon sliding the door longitudinally of the rail when in its extended position the rib will not bind.

As the sleeve, 26, pivots about the rail and the caster is moved transversely thereof, the distance of the studs, 31, from the center of the rail will vary, and this variation will be allowed by the elongated slots, 30. The engagement of the studs, 31, with the ears, 28 and 29, prevents removal of the door from the track.

The door is latched in its open position against the car frame, and in closed position by means of hooked levers, 41 and 42, respectively, having hooks, 43 and 44, respectively, co-acting with keepers, 45 and 46, respectively, secured to the door posts, 11 and 12, respectively. The lever, 41, is pivoted to the face of the door, and the lever, 42, to the edge of the door on its opposite side. The hooks, 43 and 44, are so formed that as they are hooked within the keepers they will tend to draw the door toward closed position and toward the door frame, respectively.

The ends of the levers may be secured in keepers, 47 and 48, respectively, adapted to receive pins, 49 and 50, respectively, to lock the same in place.

The ordinary sealing device, 50, is provided for sealing the door in closed position.

An opening, 51, is provided in each of the sockets, 22, which is so positioned that a pin, 52, received therein will engage the edge of the ear, 29, of the respective socket, 75 as indicated in dotted lines in Fig. 3, so as to lock the sleeve, 26, against pivotal movement relative to the socket.

It will now be seen that by disengaging the devices, 41, 42 and 50, the door may be slid to the right, in the construction shown in the drawings, until the socket, 22, engages the bracket, 17. In such position the edge of the door will have cleared the edge of the door opening, since the bracket, 80 A, extends to the left of the edge of the door, and the bracket, 17, is positioned approximately at the edge of the door opening, which is not illustrated in the drawings.

When the door is in closed position, as shown, the bracket, B, which is extended to the right of the door, will allow the door to extend its position to entirely close the door opening, while the socket remains on the remote side of the bracket, 17, from the door.

Ordinarily the door will be manipulated in the position in full lines in the figures, in which position the rollers, 25, will ride upon the rail, as shown in Fig. 3. Should the door, however, become held by the accumulation of dung against the side thereof, in the door opening, or by water or mud freezing between the door and door posts, it may be moved to its extended position 100 and thence rolled along the track clear of the foreign material. In some cases a bulge in the side of the car will interfere with the rolling of the door, and such bulge may ordinarily be cleared by the door when in extended position.

Some changes may be made in the construction and arrangement of the parts of my invention without departing from the real spirit and purpose of my invention, 115 and it is my intention to cover by my claims any modified forms of structure or use of mechanical equivalents which may be reasonably included within their scope.

I claim as my invention:

1. In a car door construction, a rail, a door, casters carried by said door at its bottom and having a rolling engagement with the rail, said casters including rollers slideable transversely upon the rail, and guide sleeves slidably and rotatably mounted upon the rail, said sleeves each having a connection with a respective caster, preventing removal of the caster from the rail, yet allowing it to move transversely of the rail,

- pairs of stops on the casters, and projecting ears on the sleeves extending between the stops of the respective pairs, and adapted to engage the stops to limit said transverse movement.
2. In a car door construction, a rail, a door, casters carried by said door at its bottom and having a rolling engagement with the rail, said casters including rollers slideable transversely upon the rail, and guide sleeves slidably and rotatably mounted upon the rail, said sleeves each having a connection with a respective caster, preventing removal of the caster from the rail, yet allowing it to move transversely of the rail, and inter-engaging means on the respective sleeves and casters, limiting such transverse movement.
3. In a car door construction, a rail, a door, casters carried by said door at its bottom and having a rolling engagement with the rail, said casters including rollers, slideable transversely upon the rail, and means connecting the casters to the rail to prevent removal therefrom, said means allowing movement of the casters transversely of the rail, and limiting such transverse movement.
4. In a car door construction, a rail, a door, bearing elements carried by the door at its bottom and resting upon the rail for movement longitudinally thereof, said bearing members being movable transversely of the rail, and guide sleeves, slidably and rotatably mounted upon the rail, each sleeve having a connection with a respective bearing element, preventing removal of said element from the rail, yet allowing it to move transversely of the rail, pairs of stops on the bearing element, and projecting ears on the sleeves extending between the stops of the respective pairs, and adapted to engage the stops to limit said transverse movement.
5. In a car door construction, a rail, a door, bearing elements carried by the door at its bottom and resting upon the rail for movement longitudinally thereof, said bearing members being movable transversely of the rail, and guide sleeves, slidably and rotatably mounted upon the rail, each sleeve having a connection with a respective bearing element, preventing removal of said element from the rail, yet allowing it to move transversely of the rail, and inter-engaging means on the respective sleeves and bearing elements, limiting such transverse movement.
6. In a car door construction, a rail, a door, bearing elements carried by the door at its bottom and resting upon the rail for movement longitudinally thereof, said bearing members being movable transversely of the rail, and means rotatable and slideable upon the rail and connected to the bearing elements to prevent removal of said bearing elements from the rail and to limit such transverse movement.
7. In a car door construction, a rail, a door, casters carried by said door at its bottom, said casters including socket members, rollers journaled in said socket members and resting against the rail for rolling movement longitudinally thereof, and sliding movement transversely thereof, and sleeves slidably mounted on said rail and provided with arms embracing said sockets and attached to said sockets by pin and slot connections, allowing limited movement of the sockets away from the axis of the rail between said arms.

Signed at Sioux City, in the county of Woodbury and State of Iowa, this 11th day of November, 1925.

THOMAS F. LACY.
